UNITED STATES PATENT OFFICE.

JOHN W. MILLER, OF TOLEDO, OHIO.

TRAFFIC SIGNAL.

Application filed February 17, 1923. Serial No. 619,660.

To all whom it may concern:

Be it known that I, JOHN W. MILLER, a citizen of the United States, residing at Toledo, in the county of Lucas and State 5 of Ohio, have invented certain new and useful Improvements in Traffic Signals; and I do hereby declare the following to be a full, clear, and exact description of the invention, such as will enable others skilled 10 in the art to which it appertains to make and use the same.

The invention has relation to vehicular signaling means for controlling traffic and preventing casualties, since it is the intention 15 to provide a motor vehicle with signaling means under control of the driver, whereby it may be known when a turn to the right or to the left, or the vehicle is to be brought to a stop, or to be directed 20 straight ahead, may be indicated, so that drivers of other vehicles and pedestrians may be duly informed of the intention of a driver so as to avoid confusion and a possible accident.

25 Other objects and advantages will be apparent and suggest themselves as the nature of the invention is understood.

While the drawings illustrate an embodiment of the invention it is to be understood 30 that in adapting the same to meet different conditions and requirements, various changes in the form, proportion and minor details of construction may be resorted to without departing from the nature of the invention.

35 Referring to the accompanying drawings forming a part of the application,

Figure 1 is a front view illustrative of the invention,

Figure 2 is a top plan view of the parts 40 shown in Figure 1,

Figure 3 is a sectional detail of the indicator and operating mechanism,

Figure 4 is a detail perspective view of the hand wheel for operating the signal and the detent in cooperative relation therewith,

Figure 5 is a sectional detail of the indicator, and

Figure 6 is a detail view of the inner extension of the supporting arm and shaft 50 showing the hand wheel in section.

Corresponding and like parts are referred to in the following description and designated in the several views of the drawings by like reference characters.

55 The numeral 1 designates an arm having

a clamp 2 at its inner end for attachment to the frame of the windshield of a motor vehicle or other convenient part of the machine, said arm having an inner extension 3 which terminates within convenient reach 60 of the driver. The outer end of the arm 1 is deflected laterally, as indicated at 4, and pivotally supports an indicator 5. The indicator may be of any preferred form and, as shown, has the outline of an arrow and consists of a metal casing open at opposite sides to which transparent plates 6 are fitted, whereby to shed rays of light forwardly and rearwardly. The indicator 5 is mounted to turn in a vertical plane, whereby to point 70 laterally in either direction to designate the intention to turn to the right or to the left, or to point upwardly or downwardly to indicate the intention to go straight ahead or to stop. A light 7 is located at the inner 75 end of the indicator and preferably consists of an electric lamp to which current is supplied from a suitable source by means of lead wires 8.

Any suitable means may be provided for 80 operating the indicator and, as shown, a bevel gear 9 is fast to the axis of the indicator and is in mesh with a companion bevel gear 10 secured to a shaft 11 which is journaled to the arm 1 and the extension 3 85 thereof and is provided at its inner end with a hand wheel 11' formed with notches 12 to coact with a spring detent 13, whereby to hold the indicator in any one of four operative positions, when moved to indicate 90 the intention of the driver to make a turn either to the right or to the left, or to bring the vehicle to a stop, or to go straight ahead. A reflector 14 is disposed at the inner end 95 of the indicator 5 to diffuse the rays of light throughout the same, and the transparent side plates 6 are outwardly converged to insure their illumination throughout.

The arm 1 has a bearing sleeve 15 at its outer end in which is journaled a hollow 100 spindle 16 attached at its lower end to the indicator 5. The wires 8 pass through the spindle 16 and enter the indicator casing and emerge through the rear wall and connect with a lamp socket 17 in any preferred 105 way.

What is claimed is:

In an operating device for a vehicular traffic signal comprising a support, a bearing sleeve carried by said support, a spindle 110

rotatably carried in said sleeve and adapted to operate the indicator, a shaft mounted upon said support, a hand wheel fast upon the inner end of said shaft and provided with notches on one face thereof, a lateral extension on said support, and a spring detent carried by said extension and adapted to coact with said notches to hold said spin-

dle and its operating mechanism in the required adjusted position.

In testimony whereof I affix my signature in presence of two witnesses.

JOHN W. MILLER.

Witnesses:

JOHN A. REYNOLDS,
RAY R. HOWE.
